UNITED STATES PATENT OFFICE

149,103

DESIGN FOR A NECKTIE RACK

Allen L. Atkins, Chicago, Ill.

Application September 12, 1946, Serial No. 133,272

Term of patent 14 years

(Cl. D33—8)

To all whom it may concern:

Be it known that I, Allen L. Atkins, a citizen of the United States and a resident of Chicago, in the county of Cook and State of Illinois, have invented a new, original, and ornamental Design for a Necktie Rack, of which the following is a specification, reference being had to the accompanying drawing, forming a part thereof.

Fig. 1 is a perspective view of a necktie rack showing my new design as it appears with the supporting beam in horizontal position;

Fig. 2 is a side elevational view thereof with the supporting beam in vertical position; and

Fig. 3 is a sectional view thereof taken approximately on line 3—3 of Fig. 1.

I claim:

The ornamental design for a necktie rack, as shown and described.

ALLEN L. ATKINS.
